The Schedule referred to in these Letters Patent and making part of the same.

To all whom it may concern:

Be it known that

I, Samuel H. Ransom of the City of Albany and State of New York have produced a new Ornamental Design, for an Elevated oven to be attached to and used with Cooking Stoves, and I do declare the annexed and accompanying drawing to be a full and perfect description of the same, the parts of the said oven not represented in the drawing, being similar to and symmetrical with the corresponding parts of the oven as represented.

What I claim as my invention and desire to secure by Letters Patent is the combination and arrangement of ornamental figures and forms represented in the drawings, the same forming an Ornamental design for an elevated Oven.
